GAS DISCHARGE TUBE

Edward S. Woolrich, Cleveland Heights, Ohio,
assignor, by mesne assignments, to Flexlume
Corporation, Tonawanda, N. Y., a corporation
of New York

Application June 6, 1929, Serial No. 368,789

9 Claims. (Cl. 176—126)

This invention relates to luminous electrical discharge tubes of the type employing an inert gas such as neon as the current conducting medium, such tubes being extensively used for illuminated signs.

In tubes of the character above referred to, the metallic electrodes at the ends of the tube become heated by the electric bombardment to such an extent that the metal at certain exposed points on the electrode is vaporized and deposited on the walls of the glass tube. This, of course, is objectionable, not only because of the blackening of the tube and of the metal deposit, but also because the deposit absorbs the gas in the tube and shortens the life of the tube.

It is a property of the conduction of electricity that the electric current at any point in a conductor tends to follow a path normal to an equipotential surface. In case of conduction through gas, this phenomena is modified by the momentum of the electrified bodies which tends to keep them on their course.

In a luminous tube, the electric stream is not evenly distributed within the tube. The distribution is dependent among other things on the gas pressure within the tube. Where gas exists in a tube, a certain number of electrons are deflected from their normal course and tend to strike the walls of the tube. If, as is usually the case, the walls are composed of a non-conducting surface such as glass, the glass receives a negative charge from the few electrons that find lodgment thereon and this space charge tends to deflect the stream of electrons toward the center of the tube, this phenomenon being greater, the greater the pressure of the filling.

This deflection is further influenced by the fact that the electrons, due to their frequent collision with the atoms in the tube do not have the velocity which they would have in a more completely evacuated tube. The receiving surface of the electrode, whatever its form, is an equipotential surface. In moving away from the surface of the electrode, further equipotential surfaces exist which at first follow the surface of the electrode very closely, but are deformed as the distance from the electrode increases until they take the form which exists in the main body of the tube which, owing to the charge on the glass tube, is convex to the stream of electrons. The passage of the stream through these convex equipotential surfaces tends to concentrate the stream of electrons toward the longitudinal axis of the tube, although this is opposed by the mutual repulsion of the electrons themselves.

Where a cathode has a convex surface exposed to the electric stream, the concentration of the electric stream is increased in proximity to such surface and a very large proportion of the positively electrified ions impinge on the convex surface. For this reason, in the case of the cup-shaped internal electrode, such as is commonly used in the luminous tube industry, the electric stream is largely concentrated upon the edge of the cup.

In the case of cup-shaped electrodes with the edge of the cup fused to the edge of the glass tube, there is a tendency for the current of the electrodes to be distorted so that a large proportion of the stream of ions strikes the electrode close to the seal.

In the case of the internal cup-shaped electrode, the concentration of the stream of ions causes excessive heating of the edge of the cup and vaporization of the metal along this edge.

In case of a cup-shaped electrode sealed to the end of the tube, the concentration of the stream of ions at the edge of the glass seal causes excessive heating which may damage or destroy the seal which is the weakest point of the structure.

The present invention has for its object to provide means for controlling distribution of the stream of ions adjacent the electrodes of a luminous discharge tube in such a manner as to prevent damage to the electrode either by vaporization of metal or by destruction of the seal.

A further object of the invention is to provide, in the tube adjacent the electrode, an electrically conductive means which does not have a direct electrical connection to the electrode and which receives an electrical charge of opposite sign from that of the electrode, forming an equipotential surface serving to disperse portions of the stream of ions which would normally have an excessive heating action on portions of the electrode.

With the above and other objects in view, the invention may be said to comprise the electrical discharge tube as illustrated in the accompanying drawing hereinafter described and particularly set forth in the appended claims, together with such variations and modifications thereof as will be apparent to one skilled in the art to which the invention appertains.

Reference should be had to the accompanying drawing in which:

Figure 1 is a sectional view showing an electrical discharge tube having an internal cup-shaped electrode and an element in the form of

a wire ring positioned adjacent the open inner end of the electrode.

Fig. 2 is a sectional view showing the same electrode with an element in the form of a tapering coil positioned adjacent the inner end of the electrode.

Fig. 3 is a sectional view showing an element in the form of a coil surrounding the cup-shaped electrode and projecting beyond the inner end thereof.

Fig. 4 is a sectional view showing two elements, one surrounding and the other positioned beyond the inner end of the cup-shaped electrode.

Fig. 5 is a sectional view showing a luminous discharge tube which is provided with a cup-shaped electrode sealing the end of the glass tube and provided with an element in the form of a tapering coil within the glass tube at the end thereof.

Fig. 6 is a sectional view showing a luminous discharge tube having an electrode such as shown in Fig. 1 and an element in the form of a wire ring which is coupled capacitatively with the electrode.

Fig. 7 shows a luminous discharge tube having the same electrode as in Fig. 5, but with a ring shaped element coupled to the electrode through an impedance.

Referring to the accompanying drawing, Figs. 1 to 4 and Fig. 6 of the drawing illustrate the invention as applied to a luminous discharge tube having an internal cup-shaped electrode and in these views, the glass tube is designated by the reference numeral 1 and the electrode by the reference numeral 2. The cup-shaped electrode 2 is supported within the tube with its open end presented inwardly and is coupled to a suitable source of current by means of a lead in wire 3 extending through and sealed in a thickened portion 4 at the end of the glass tube, the lead in wire being welded, soldered or otherwise rigidly secured to the closed end of the electrode and serving to support the electrode in the tube. The electrode above described is old and well known, the present invention comprising means in the vicinity of the electrode for so controlling the stream of ions as to prevent localized heating of the electrode.

As shown in Fig. 1 of the drawing, the controlling means consists of an element in the form of a wire ring 5 supported adjacent to but out of contact with the edge of the cup-shaped electrode 2. The ring 5 may be supported independently of the electrode in any desired manner. As shown in Fig. 1, the wire forming the ring has one end 6 extending along the outside of the cup out of contact therewith and embedded in the thickened portion 4 of the glass tube.

The ring 5 forms an annular equipotential surface adjacent the open end of the cup-shaped electrode which acts to concentrate the stream of ions toward the axis of the tube adjacent the open end of the cup so that the major portion of the stream is caused to pass into the cup before it is dispersed by the action of the electrode with the result that the major portion of the stream of ions is dispersed over the interior surface of the cup and concentration of the stream on the edge of the cup is prevented.

In Fig. 2 of the drawing, the element is in the form of a wire coil 7 of tapering form supported centrally of the tube inwardly of the electrode with its small end within or closely adjacent the open end of the cup-shaped electrode. The coil

7 may be supported out of direct electrical con-

tact with the electrode by an end portion 8 of the coil extending along the wall of the tube 1 outside the electrode 2 and embedded in the thickened portion 4 of the glass tube. As in the case of the ring shaped element, the wire coil forms an equipotential surface adjacent the electrode concentrating the stream of ions adjacent the free edge of the cup shaped electrode and causing the same to be dispersed over the interior surface of the electrode.

In the modification shown in Fig. 3 of the drawing, the element is in the form of a coil 9 surrounding the electrode 2 and projecting beyond the open inner end thereof, the wire at one end of the coil extending along the wall of the glass tube to form a supporting extension 10 which is embedded in the glass at the end of the tube. As in the modifications previously described, the coil 9 is supported out of electrical contact with the electrode and serves to drive the stream of ions away from the edge of the cup-shaped electrode 2.

In the modification shown in Fig. 4 of the drawing, two elements which are adapted to receive charges differing in potential are employed, one of the elements being a tapering coil beyond the inner end of the electrode similar to the coil 7 shown in Fig. 2 and the other being a coil 11 surrounding the electrode. The two coils 11 and 12 are supported out of electrical contact with each other and out of electrical contact with the electrode by means of extensions 13 and 14 of the wire coils which are embedded in the glass of the tube.

It is essential that the element which is composed of metal or other electrically conductive material receive a charge differing in potential from that of the electrode and, in the modifications above described, the elements are shown entirely disconnected from the electrode. The said element, therefore, in these embodiments is not connected to power and hence no lead in wire is employed in connection with it. It is to be understood, however, that any of the elements herein disclosed may be coupled to the electrode either capacitatively, as illustrated in Fig. 6 or through an impedance as illustrated in Fig. 7.

In Figs. 5 and 7, the invention is illustrated as applied to a luminous discharge tube in which the glass tube 15 has an open end sealed by a cup-shaped electrode 16, the open end of which is sealed to the end of the glass tube 15.

In Fig. 5 of the drawing, the element is in the form of a tapering wire coil 17 having its small end adjacent the end of the tube, which is sealed within the end of the cup-shaped electrode 15 and is supported by an extension 18 of the wire at the upper end of the coil, which is embedded in the glass wall of the tube. The coil 17 serves to concentrate the major portion of the stream of ions to such an extent that it will be carried past the seal and distributed over the interior surface of the electrode, thus preventing overheating of the electrode along the edge of the seal.

In Fig. 6 of the drawing, there is shown an element in the form of a wire ring 19 which may be embedded in the glass wall of the tube a short distance inwardly of the edge of the electrode. The wire ring 19 acts upon the electron stream in a manner similar to the ring 5 in Fig. 1 and may, if desired, be coupled capacitatively with the electrode 16 through a suitable condenser 21.

In Fig. 7 of the drawing, there is shown a wire ring element 22 similar to the element shown in

Fig. 6 but coupled with the electrode 16 through an impedance coil 23.

In all of the modifications above described, the concentration of the stream of ions on certain exposed portions of the electrodes, which in the operation of the tubes act alternately as anodes and cathodes, is prevented by providing an equi-potential surface so disposed with respect to the portions of the electrode to be protected as to force the major portion of the stream away from the portions of the electrode which it is desired to protect whereby a more even distribution of the stream of ions over the surface of the electrode is obtained and localized heating of the electrode is avoided. The means by which the stream of ions is controlled in the vicinity of the electrodes absorbs a considerable part of the heat generating energy of the stream and hence reduces to a considerable extent the heating action of the stream upon the electrodes. It will be apparent, therefore, that inasmuch as the said means is also utilized to control the direction of the concentrated stream that the practice of the invention enables the use of electrodes having relatively small active surfaces. The concentration of the stream of ions in the manner described does not affect the voltage drop across the electrodes. Hence the invention may be employed with various forms or sizes of electrodes while preserving this desirable characteristic. It will also be apparent that the distribution and control of the stream of ions in the manner described have the advantage that the electrodes may be composed of metals which while desirable because of their low drop have not heretofore been capable of withstanding the bombarding action to which they have been subjected where the stream of ions has not been controlled. For example, electrodes of magnesium, or principally of magnesium are desirable because of their low drop. The present invention, therefore, enables the use of electrodes of such a metal.

Furthermore, it is to be understood that the particular form of apparatus shown and described, and the particular procedure set forth, are presented for purposes of explanation and illustration and that various modifications of said apparatus and procedure can be made without departing from my invention as defined in the appended claims.

What I claim is:

1. A luminous electrical discharge tube having a cup-shaped electrode mounted with its open end facing inwardly, and an element in the form of a wire coil supported coaxially with the electrode, and out of contact therewith adjacent the open end thereof.

2. In a luminous electrical discharge tube, the combination with an elongated glass tube containing a gas which acts as a current conducting medium and having electrodes at the ends thereof, of means for controlling the stream of ions in the vicinity of the electrodes comprising an element of electrically conductive material in the tube adjacent each electrode, each element being coupled capacitatively with its respective electrode.

3. A luminous electrical discharge tube having a cup-shaped electrode, and an annular element of electrically conductive material within the tube adjacent the edge of the cup-shaped electrode,

said element being coupled capacitatively with the electrode.

4. In a luminous electrical discharge tube, the combination with an elongated glass tube containing a gas which acts as a current conducting medium and having electrodes at the ends thereof, of means for controlling the stream of ions in the vicinity of the electrodes comprising an element of electrically conductive material within the tube adjacent the inner end of each electrode and adapted to receive an electrical charge of a potential different from that of the electrode, each element being electrically coupled with its electrode and an impedance interposed between the element and electrode.

5. A luminous electrical discharge tube having a cup-shaped electrode, and an annular element of electrically conductive material within the tube adjacent the edge of the cup-shaped electrode, said element being electrically coupled with its electrode and an impedance interposed between the element and electrode.

6. A luminous electrical discharge tube having a cup-shaped electrode mounted with its open end facing inwardly, and an element in the form of a wire coil supported coaxially with the electrode, and out of contact therewith adjacent the open end thereof, said coil being of tapered form and having its small end adjacent the open end of the electrode.

7. A luminous electrical discharge tube, the combination with an elongated glass tube containing a gas which acts as a current conducting medium and having an electrode at an end of the tube, of means for controlling the stream of ions in the vicinity of the electrode comprising an element of electrically conductive material within the tube adjacent the inner end of the electrode and spaced inwardly from said end, said element being insulated from said electrode and having no lead in wire.

8. In a luminous electrical discharge tube, the combination with an elongated glass tube containing a gas which acts as a current conducting medium and having electrodes at the ends thereof, of means for controlling the stream of ions in the vicinity of the electrodes comprising an element of electrically conductive material in the tube adjacent each electrode, said element being formed with a relatively large opening in the direction of the body of the tube and tapering from said opening in the direction of the electrode with which it is associated to a relatively smaller opening whereby the stream of ions passing through the said element emerges therefrom in a concentrated condition.

9. In a luminous electrical discharge tube, the combination with an elongated glass tube containing a gas which acts as a current conducting medium and having hollow open ended electrodes at the ends thereof, of means for controlling the stream of ions in the vicinity of the electrodes comprising an element of electrically conductive material in the tube adjacent each electrode, said element being formed with a relatively large opening in the direction of the body of the tube and tapering from said opening in the direction of the electrode with which it is associated whereby the stream of ions as it passes through the said element is concentrated and directed into the interior of the electrode.

EDWARD S. WOOLRICH.
